DESIGN FOR A COMBINATION LETTER OPENER AND PAPERWEIGHT

Leonard F. Johnson, Arlington, Va.

Application March 29, 1946, Serial No. 128,061

Term of patent 14 years

(Cl. D74—12)

To all whom it may concern:

Be it known that I, Leonard F. Johnson, a citizen of the United States, residing at Arlington, in the county of Arlington and State of Virginia, have invented a new, original, and ornamental Design for a Combination Letter Opener and Paper Weight, of which the following is a specification; reference being had to the accompanying drawing, forming a part thereof.

Figure 1 is a side elevational view of a combination letter opener and paper weight, showing my new design;

Figure 2 is an edge elevational view.

Figure 3 is a top plan view thereof; and

Figure 4 is an edge elevational view of the opposite side of the article shown in Figure 2.

Figure 5 is an edge elevational view of the letter opener element.

I claim:

The ornamental design for a combination letter opener and paper weight, as shown.

LEONARD F. JOHNSON.
